UNITED STATES PATENT OFFICE.

ROBERT SCHMIDT, OF BOSTON, MASSACHUSETTS.

CHAIR.

Application filed January 4, 1923. Serial No. 610,632.

To all whom it may concern:

Be it known that I, ROBERT SCHMIDT, a citizen of the United States, residing at Boston, in the county of Suffolk and State 5 of Massachusetts, have invented certain new and useful Improvements in a Chair, of which the following is a specification.

The present invention relates to a chair and the subject matter thereof has been disclosed from my pending application bearing Serial Number 526,169, filed on the 31st of December, 1921.

The principal object of the invention is to provide a shelf or tray mounted on a chair so that it may be disposed in extension of the back when not in use.

With the above and numerous other objects in view as will appear as the description progresses, the invention relates to certain novel features of construction and the combination and arrangement of parts as will be hereinafter fully described and claimed.

In the drawing—

Figure 1 is a perspective view of the chair embodying my invention,

Figure 2 is a fragmentary side elevation thereof, and

Figure 3 is a detail perspective of one arm 30 of the tray or shelf.

Referring to the drawing in detail it will be seen that the legs of the chair 1 are preferably four in number and the two rear legs extend upwardly so as to form the supports 35 2 for the back rest 3. The front legs extend upwardly so as to form the supports 4 for the arm rests 5 which are attached at their rear ends intermediately to the supports 2. These parts of the chair are conventional 40 and may be of any preferred construction.

In order to form a table for the high chair I have provided a shelf 22 which when in use is situated and supported on the forward ends of the arm rests 5 as is indicated in

Figure 2 and when not in use is situated in extension of the back rest as is illustrated in Figure 1. This shelf 22 is fixed to a pair of supporting arms 23 which are longitudinally slotted adjacent their ends as indicated at 24, said slots having an offset portion at 25. A projection 27 is formed on the end of each rod 23 for engagement with stops 28 carried on the supports 2 adjacent the seat of the chair thus holding the shelf 22 in a position adjacent the upper portion of the back rest 3 so as to form a part thereof. When it is desired, however, to use the shelf as a table it is lifted so as to free the projection 27 from the stops 28 at which time it may be moved so as to rest on the forward ends of the arm rests 5, the offset portions 25 of each slot 24 engaging the pins 29 carried intermediately the ends of the supports 2. It will also be noted that this shelf may be lifted clear of the back rest 3 and is mounted 55 so as to be disposed adjacent the rear legs 1.

Having thus described my invention what I claim as new is:—

In a chair including arm rests, a shelf, a pair of arms extending from the ends of said shelf and provided with longitudinally extending slots, extensions formed on the ends of said arms, pins on the chair for engaging the slots, stops disposed on the chair below the pins for engagement by the extensions, whereby the shelf may be held in extension of the back rest of the chair, the slots in said arms being provided with offset portions so as to hold said shelf in a forward position mounted on said arm rests 75 when the pins are in engagement with the offsets.

In testimony whereof I affix my signature in presence of two witnesses.

ROBERT SCHMIDT.
